UNITED STATES PATENT OFFICE.

HENRY TRENCHARD, OF BROOKLYN, NEW YORK.

DUPLEX ENVELOPE.

Application filed November 14, 1923. Serial No. 674,598.

To all whom it may concern:

Be it known that I, HENRY TRENCHARD, a citizen of the United States, and a resident of New York city, borough of Brooklyn, Kings County, State of New York, have invented an Improvement in Duplex Envelopes, of which the following is a specification.

The present invention relates to duplex envelopes of the type providing a compartment for first-class matter which may be sealed and a compartment for third or fourth class matter such as catalogs, merchandise and the like, which need not necessarily be sealed, the contents of which can be sent at a lower rate of postage.

Such envelopes are extensively used for mailing advertising matter including a written letter which is preferably to be mailed as first class matter.

Ordinarily it is not so important that a letter of this character be delivered at any particular time, but it is highly desirable that the first-class matter and the catalog or other matter to which it relates should be received together. Envelopes of this character because they are relatively bulky and contain, in part, third or fourth class matter, are likely to be opened by those to whom they are addressed with relatively little care and, therefore, if the compartment for first class matter is not so arranged as to attract special attention, it is entirely possible and frequently occurs that the third or fourth class matter is removed from its compartment and the smaller first class matter is overlooked and thrown away with the wrapper. It has been proposed to mark the letter compartment distinctively, as for example, by printing a suitable legend thereon or by making the same of a contrasting color. However, when mail is hastily opened such marking is ineffective to direct proper attention to the letter compartment. When the letter compartment is formed to present the appearance of an entirely separate envelope, it is much more likely to be opened and much less likely to be carelessly overlooked. The tendency to extract the third or fourth class matter only and throw the container in the wastebasket without noticing the existence of a separate first class compartment is substantially reduced.

55 Duplex envelopes or containers of the

character under consideration are usually made from specially shaped blanks formed to provide the two compartments desired. The manufacture of such special envelopes in this manner, requires special dies for cutting the blanks and either special machines must be provided for folding the same or the folding operations must be performed by hand at considerable expense. Furthermore there is a demand for a variety of sizes and a variety of combinations of sizes for the first and third or fourth class matter respectively. For this reason it is necessary to carry a large stock on hand or else to manufacture specially for each order. Either practice requires a large assortment of special dies of different sizes thus increasing the expense of manufacture.

The present invention has for an object to provide an improved duplex envelope which can be manufactured expeditiously and economically.

The nature and objects of the invention will be better understood from a description of a particular illustrative embodiment thereof for the purpose of which description reference would be had to the accompanying drawing wherein.

Figure 1 is a front view of a duplex envelope embodying the principles of the invention.

Figure 2 is a sectional view taken on the line 2-2 Figure 1.

Figure 3 is a perspective view of the same.

In the arrangement shown, two envelopes are secured together in a relatively permanent manner so that they will be carried together through the mail and delivered as a unit. One envelope, as shown, the smaller, is designed for first class matter and is arranged to be sealed. The other envelope is intended for third or fourth class matter and may be closed in a relatively temporary manner, as for example, by a separable fastening means arranged to hold the flap in closed relation.

In the particular construction shown the smaller envelope 5 for first class matter is of the center seam type having a flap 6 at one end and a gummed sealing flap 7 at the opposite end. The larger envelope 9 is of the same type having a center seam 10 along what is in one aspect the back of this envelope, a sealed flap 11 at one end and a closure flap 12 at the other end. A suitable

separable fastener 14 cooperates with the flap 12 to accessibly close the envelope.

The two envelopes may be secured together in any suitable manner. Preferably they are secured together at one end only, the remaining portions being free of each other and unconnected so that as the envelope is handled it is obvious that there are two distinct mail compartments. The duplex envelope so constructed has very much the appearance of two separate pieces of mail and neither part is likely to be overlooked.

In the particular construction shown the end 15 of the smaller envelope lies relatively close to a fold of the flap 12 of the larger envelope and the fastener 14 secures the two envelopes together by passing through the smaller envelope and the back of the larger envelope as best shown in Figure 2. The fastener 14 thus constitutes means for securing the two envelopes together as well as means for holding the closure flap 12 in closed relation against the face of the smaller envelope 5 and the back of the larger envelope 9 of which it forms a part. When the flap 12 is closed and secured, any tendency of the smaller envelope to turn relatively to the larger is opposed not only by the fastener 14 but also by engagement of the end 15 of the smaller envelope in the fold of the flap 12, thus holding the two envelopes in substantially parallel relation.

The two envelopes are shown as secured together back to back. In this arrangement the flap 6 of the smaller envelope may be gummed but left unsealed when this envelope is made up and upon assembly with the larger envelope this flap may be folded within the larger envelope and secured against the inside of the back thereof. This arrangement provides a means for securing the two envelopes together which would probably be sufficient for the purpose if the fastener 14 were omitted or should tear out of the larger envelope. The flap 12 of the larger envelope 9 folds over the smaller envelope 5 against the face thereof as well as against the back of the larger envelope at either side of the smaller. In one aspect the flap 12 and the fastener 14 or other means for holding the flap closed may be considered as means for holding the two envelopes together.

The address may be applied to either of the exposed faces of the envelopes but the arrangement illustrated is preferred in which the address is applied to the face of the smaller envelope and the flap folds over such smaller envelope relatively adjacent to the address. Postage is applied to the two envelopes as indicated at 17 and 18 in the usual position with respect to the address and the two places for postage are relatively close to each other so as to be con-

venient for cancellation by the postal clerks. This arrangement is preferred for the reason that the mail as received will ordinarily be handled with the address side up and upon picking up the envelope shown it becomes quite obvious that there are two separate compartments. The two envelopes stand out at the free ends as separate units and there is a tendency to pick up the smaller envelope by itself thus making evident immediately the presence of a separate and distinct larger envelope.

Duplex envelopes embodying the present invention will be seen to embody characteristics which increase their value in use and facilitate manufacture thereof. The arrangement of the two compartments is such that it is practically impossible for one compartment to be opened and the contents removed without observing the second compartment. The connection between the two parts of the device is such that no closed pocket is formed to catch and retain other mail.

Manufacture is facilitated and the cost reduced in that no special dies, machines or tools are required. The complete article can be and preferably is made up from envelopes of standard type and a relatively small stock of the standard sizes of envelope for each type of mail can be carried on hand and the component parts of any selected sizes can be expeditiously assembled.

The larger envelope may be of regular standard type but without fasteners applied. The smaller may also be regular stock envelopes but if duplex envelopes of the preferred construction illustrated are to be made, both end flaps should be creased and gummed but not folded.

I claim:

1. A duplex envelope of the character described comprising a larger and a smaller envelope, the smaller envelope having an end flap folded within the open end of the larger envelope and secured to the inner face of the body thereof, the two envelopes being unattached throughout substantially their whole area, the closure flap at the open end of the larger envelope being foldable over the face of the smaller envelope and attachable thereto.

2. A duplex envelope of the character described comprising a larger and a smaller envelope, the smaller envelope having an end flap folded within the open end of the larger envelope and secured to the inner face of the body thereof, the two envelopes being unattached throughout substantially their whole area, the closure flap at the open end of the larger envelope being foldable over the face of the smaller envelope, a fastener securing the smaller envelope to the body of the larger envelope adjacent to the open end of the latter and arranged

to cooperate with the said closure flap of the larger envelope to hold it in closed relation.

3. A duplex envelope comprising two envelopes placed back to back with a flap of the smaller extending into and secured against the inner face of the back of the larger envelope, the closure flap of the larger envelope being foldable over the body 10 of the smaller envelope and means to secure said closure flap to the body of the smaller envelope.

4. A duplex envelope comprising a larger

envelope having a closure flap, a smaller envelope, a fastener securing the smaller 15 envelope to the larger at a point removed from the marginal edge of the smaller envelope, the marginal edge lying substantially against the fold of the flap of the larger envelope thereby to prevent rotational movement of the smaller envelope about the fastener.

In testimony whereof, I have signed my name to this specification this 12th day of November, 1923.

HENRY TRENCHARD.
